UNITED STATES PATENT OFFICE.

ALPHONSO COMSTOCK PRATT, OF DEEP RIVER, CONNECTICUT, ASSIGNOR TO WHITING & DAVIS COMPANY, A CORPORATION OF MASSACHUSETTS.

MACHINE FOR MAKING LINK MESH.

Application filed January 26, 1921. Serial No. 440,055.

To all whom it may concern:

Be it known that I, ALPHONSO COMSTOCK PRATT, a citizen of the United States, residing at Deep River, in the county of Middlesex, State of Connecticut, have invented certain new and useful Improvements in Machines for Making Link Mesh; and I do hereby declare the following to be a full, clear, and exact description of the invention, such as will enable others skilled in the art to which it appertains to make and use the same.

The present invention relates to a machine for making link mesh and involves more especially the provision in such a machine of improved means for forming the links.

In machines of this character it has been the practice to employ tools for forming the links consisting of an outer die, an anvil and an inner die. Wire is fed to the tools, cut to length and the outer die is advanced to form a staple upon the anvil. The anvil is then depressed and the inner die advanced to engage the staple and form in cooperation with the outer die, a link. Link forming mechanism of this construction is illustrated and described, for example, in Letters Patent No. 948,615 granted to me on Feb. 8, 1910, Letters Patent No. 1,028,904 granted to me on June 11, 1912, Letters Patent No. 1,144,724 granted to me on June 29, 1915, Letters Patent No. 1,317,726 granted to me on Oct. 7, 1919.

In the machine constituting the present invention separate means are provided for forming and carrying staples from which links are subsequently formed, thereby eliminating some of the parts required in the prior machines, and simplifying and facilitating the process of forming links. The machine includes a support for a piece of link mesh fabric and a carrier for staples. Means are provided for ejecting the staples from the carrier to form links and the invention also comprehends the inclusion in the machine of means acting to shift the fabric and the carrier relatively for intermeshing with the links of the fabric the links as they are formed from the staples.

Separate means may be employed for forming staples and feeding them to the carrier, and the machine may have a link forming tool which cooperates with the ejecting means to form links, preferably acting simultaneously to form a staple and a link in

one operation. Furthermore, there may be provided means adapted to shift the fabric, and also devices for actuating the shifting means and the carrier step by step to present different portions of the fabric for the addition of intermeshing links.

The invention comprehends as another of its parts certain features of construction whereby, for example, the formation of staples and links therefrom is carried out uninterruptedly so that the machine may be kept continuously in operation until the completion of the link mesh fabric. This result is produced in a machine in which there is included a support for a piece of link mesh fabric, an annulus for carrying staples, and an ejector for discharging the staples from the carrier to form links intermeshing with the links of the fabric. Furthermore, a link forming tool may be included in the machine and the ejector may cooperate with the link forming tool to form links intermeshing with the fabric. Where a link forming tool is employed there is preferably also provided devices for actuating the annulus intermittently to align each staple with the link forming tool to form links, and the annulus may have a plurality of circumferential receptacles for holding staples from which the ejector operates to discharge the staples to form links.

In the specific embodiment of the invention described hereinafter, the machine includes a support for a piece of link mesh fabric, and an annulus provided with a plurality of circumferential receptacles for holding staples. The formation of one staple and one link at a time is accomplished by providing a shuttle operating within the annulus on which there is mounted a tool for forming staples in the receptacles, and also an ejector mounted on the shuttle for discharging the staples from the receptacle. The machine also includes a link forming tool in cooperation with which the ejector operates to form links intermeshing with the links of the fabric; and means are provided for reciprocating the shuttle, together with devices for actuating the annulus and for shifting the fabric step by step to align each staple with the link forming tool and to present different portions of the fabric to the tool to receive links.

In the accompanying drawings illustrating the invention in application, as an ex-

ample, to a link mesh machine of the type illustrated and described in Letters Patent No. 948,615 granted to me on Feb. 8, 1910,

Figure 1 is a sectional elevation of the machine.

Figure 2 is a plan view of the machine along the line 2-2 of Figure 1.

Figure 3 is a detail view of the carrier.

Figure 4 is a detail plan view of a portion of the carrier, and

Figure 5 is a plan view in section of a modified form by means for forming staples in the carrier.

The machine has a table 1 upon which is supported a hollow mandrel 2 provided at its upper end with spiral grooves 3. A ring 4 suitably supported on the table 1 serves as a bearing for the sleeve 5 which surrounds the spirally grooved portion of the mandrel 3. The interior surface of the sleeve 5 is provided with a plurality of ridges and depressions as indicated at 6 in Figure 1 extending in the direction of the axis of the sleeve. Between the sleeve 5 and the mandrel 3 is a space in which the mesh fabric 60 being made by the machine is adapted to lie. As the link mesh fabric is formed it is raised step by step on the mandrel 3 by the rotation of the sleeve 5, the ridges and depressions in which grip corresponding ridges and depressions formed by the links of the fabric, the links following the spiral grooves as they are made. The step by step rotation of the sleeve within the ring 4 is effected by means of a ratchet and pawl, the exterior of the sleeve having ratchet teeth 7 which are engaged by a spring pressed pawl 8. The pawl 8 is mounted in an opening 9 in shaft 10 which extends downwardly through the table 1 and is supported at its lower end by a bearing 11. Secured to the lower end of the shaft 10 is a crank 12, the end of which carries a roller 13 bearing against the periphery of a cam 14. The crank 12 is actuated by the cam 14 to rock the shaft 10 in its bearings and thus move the pawl 8, the movement of the shaft 10 being equal to one of the ratchet teeth 7. The cam 14 is mounted on a power shaft 15 which is supported in bearings 16 carried by the table 1 and connected to a suitable source of power.

The mandrel 3 has a radial opening 17 in which a die 18 is mounted. The die 18 is provided with a notch 19 near its inner end in which is fitted the end of a spring finger 20 secured at 21 to the inner wall of the mandrel. Reciprocating within the mandrel 3 is a plunger 22, one end of which is secured to a cross head 23 and the other end carrying a guide 24 fitted within the mandrel. The plunger 22 is provided with a cam surface 25 which coacts with the cam surface 26 at the inner end of the die 18

when the plunger 22 is reciprocated by the cross head 23 and the crank 27 operated by the power shaft 15. The die 18 is normally held in the position indicated in Figure 1 by the spring finger 20 and is advanced to 70 form a link through the coaction of the cam surfaces 25 and 26 when the plunger 22 is raised.

The parts of the machine thus far indicated are the same as the corresponding parts in Letters Patent No. 948,615 granted to me on February 8, 1910, and reference is to be had to this patent for the complete details of these parts.

Supported on the table 1 is a bearing ring 28 upon which is mounted an annulus 29. The annulus 29 is locked in position on the bearing ring 28 by means of a locking ring 30 threaded on the end thereof. Affixed to the upper surface of the annulus 29 is a plurality of radially disposed abutments 31 having grooves 32 cut in their side walls which provide receptacles for the reception of the staples having grooves 32 cut in their side walls for the reception of the staples. 80 Mounted to reciprocate in a guide way 33 in the bearing ring 28 is a slide 34 which supports at one end the staple forming tool and at its upper side a tool for ejecting the staples from the receptacles and which co-85 operates with the die 18 to form links. The die rod 35 is carried in one end of an upright member 36, the other end of which is adjustably fastened as at 37 to the outer extremity of the arm 38 extending from the end of the slide 34. The arm 38 projects through an opening 39 in a block 40 supported on the table 1. Mounted in the upper end of the block 40 is a slide 41 through 90 an opening in which the die rod 35 moves. The slide 41 is provided with a cutting edge 42 for severing a length of wire from which 95 a staple is formed. The ejector 43 consists of an upwardly extending inwardly bent rod having a die 44 at its inner extremity, and which is secured to the upper surface of the slide 34. The under side of the slide 34 carries a pair of brackets 45 which are secured to one end of a crank 46 by means of a pin 47 passing through a slot 48 in the crank arm. The opposite end of the crank 46 is connected to a lever 49 which is pivoted at 50 to the cross head 23 by which a reciprocatory motion is imparted through the lever 49 and the crank 46 to 100 the slide 34. 105

Cut in the outer periphery of the annulus 29 are ratchet teeth 51, which are engaged by a spring pressed pawl 52, mounted in an opening 53 in a shaft 54, the latter being 110 supported in suitable bearings on the table 1. The shaft 54 is rocked simultaneously with the shaft 10 by connection with the latter through the crank arm 55, the lever 56 and a crank arm 57, said crank arms and 115 120

125 130

lever being pivotally connected together as at 58 and 59.

Mounted on the table 1 is a block 61 in an opening in which reciprocates a bent arm 62 which is pivotally connected at 63 to a link 64, the latter being in turn pivoted at 58 to the crank arm 57. The end of the arm 62 has a cam surface 63^a which coacts with the cam surface 64^a of a slide 65 to force the latter downwardly in Figure 2. The slide 65 reciprocates in a block 66 on the table 1 and the return movement of the slide, in an upward direction, Figure 2, is effected by a spring 67 in the block. Secured to the 15 slide 66 is a spring pressed pawl 68 which engages a ratchet wheel 69 arranged to actuate one of a pair of superimposed friction rollers 70 connected together by means of gear wheels 71. These friction rollers feed 20 the wire 72 into the block 40 through a guide 73 and thus in the path of the slide 41 and the die rod 35.

Situated between the upright member 36 and the slide 41 is a spring 74 so that when 25 the slide 34 is moved inwardly toward the mandrel, carrying with it the die rod 35, the inward motion is also imparted to the slide 41 by the spring 74. The inward movement of the slide 40 is limited by an adjustable stop 75 which permits a sufficient 30 movement of the slide to effect the cutting of the wire and the return movement of the slide, after the cutting operation and the formation of a staple, is effected by a key 35 76 sliding in a groove 77 cut in the slide 41.

The machine operates to form and feed a staple to the carrier and simultaneously to form a link which is added to the link mesh fabric 60 supported on the mandrel 3, since 40 the staple forming die 35 and the ejector 43 provided with the die 44 are both carried by the slide 34. When the shaft 10 is rocked by the cam 14, the sleeve 5 is rotated and the link mesh fabric 60 moved to a position 45 to receive a link. At the same time the annulus 30 with the staple receptacles 31, constituting the carrier, is rotated a step to bring an empty receptacle in position in front of the staple forming die and a receptacle carrying a staple 78 in the path of the ejector 43 and the link forming dies 44 and 18. The rocking of the shaft 10 is also communicated to the feed wire mechanism and a length of wire is fed into the block 40 in the 50 path of the staple forming tools. The slide 34 moves inwardly through the connection with the cross head 43 and both the staple forming tools and the ejector are advanced to simultaneously form a staple, feed it to 55 the carrier, and discharge a staple from the carrier to form, by means of the dies 44 and 18, a link intermeshing with the link mesh fabric.

The die rod 35 for forming the staples 60 above described operates to form a staple

from the severed length of wire by projecting it through a slot 79 in the block 40, and thus it will be seen that the staple is already formed when fed to the staple receptacle of the carrier, the wire being bent in 70 the form of a staple in its passage through the slot.

A modified form of staple forming die is illustrated in Figure 5. In this form the die 80 is mounted on the ends of slide 41 75 which carries a knife 81 projecting therefrom, the knife edge being approximately opposite the end of the die 80. In this arrangement when the slide 41 is advanced the knife severs a length of wire and continues 80 in its forward movement through the opening 82 while the die 80 forces the severed length of wire into the staple receptacle wherein the staple is formed.

As heretofore pointed out the present invention has reference more particularly to the carrier for staples which may, as illustrated in the drawings, be employed in conjunction with the type of machine in which the link mesh fabric is made in the form 90 of a sleeve. Such a machine is usually provided with four sets of link forming tools, the mandrel having four radial openings within which the inner link forming dies reciprocate. In the machine illustrated in 95 the drawing but one such die, reciprocating in a single radial opening in the mandrel, is illustrated, but it will be understood that any desired number of dies may be employed in conjunction with a corresponding number 100 of carriers to form a plurality of links in one operation.

What I claim is:

1. In a machine for making link mesh, a support for a piece of link mesh fabric, a carrier, means for forming staples and placing them in the carrier, means for ejecting the staples from the carrier and forming them into links meshing with those of the fabric on said support and mechanism for 105 effecting a relative movement between the fabric on said support and the said ejecting and forming means so as to present new points on the piece of fabric successively for the reception of the newly formed links. 115

2. In a machine for making link mesh, a support for a piece of link mesh fabric, a carrier for staples, means for forming staples and feeding them to the carrier, means for ejecting the staples from the carrier to form links, and means acting to shift the fabric and the carrier relatively for intermeshing with the links of the fabric the links as they are formed from the staples. 120

3. In a machine for making link mesh, a support for a piece of link mesh fabric, a carrier for staples, means for forming and feeding a staple to the carrier, means for simultaneously ejecting a staple from the carrier to form a link, and means acting to shift 125 130

- the fabric and the carrier relatively for intermeshing with the links of the fabric the link formed from the staple.
4. In a machine for making link mesh, a support for a piece of link mesh fabric, a carrier for staples, means for forming staples and feeding them to the carrier, means for ejecting the staples from the carrier, a link forming tool cooperating with said ejecting means to form links and means acting to shift the fabric and the carrier relatively for intermeshing with the links of the fabric the links as they are formed from the staples.
5. In a machine for making link mesh, a support for a piece of link mesh fabric, a carrier for staples, means for forming staples and feeding them to the carrier, means for ejecting the staples from the carrier, a link forming tool cooperating with said ejecting means to form links, means adapted to shift the fabric, and devices for actuating said shifting means and said carrier step by step to present different portions of the fabric for the addition of intermeshing links.
6. In a machine for making link mesh, a support for a piece of link mesh fabric, a circular member for supporting and carrying staples, means for forming staples and placing them upon the said member successively, means for rotating the member step by step to carry the staples thereon successively to an ejecting position, devices for ejecting the staples from said member and forming them into links meshing with those of the said piece of fabric, and means for effecting a relative step by step movement between the said support and the said ejecting and forming devices.
7. In a machine for making link mesh, a support for a piece of link mesh fabric, a carrier, means for forming staples and placing them upon the carrier, means for moving the carrier step by step, a link-forming device, a member movable to remove a staple from the carrier, link it with links of the said fabric and carry it into cooperation with the said link-forming device to form the staple into a link, and means for effecting a relative step by step movement between the piece of fabric on the support and the said link-forming device.
8. In a machine for making link mesh, a support for a piece of link mesh fabric, an annulus for carrying links, a tool for forming and feeding staples to said annulus, a link forming tool, and an ejector for discharging the staples from the annulus and cooperating with the link forming tool to form links intermeshing with the links of the fabric.
9. In a machine for making link mesh, a support for a piece of link mesh fabric, an annulus for carrying links, a tool for forming and feeding staples to said annulus, a link forming tool, an ejector for discharging the staples from the annulus and cooperating with the link forming tool to form links intermeshing with the links of the fabric, and devices for actuating said annulus intermittently to align each staple with the link forming tool.
10. In a machine for making link mesh, a support for a piece of link mesh fabric, an annulus provided with a plurality of circumferential receptacles for holding staples, a tool for forming staples in said receptacles, a link forming tool, an ejector for discharging staples from said receptacles and cooperating with the link forming tool to form links intermeshing with the fabric, and devices for actuating said annulus intermittently to align each staple with the link forming tool.
11. In a machine for making link mesh, a support for a piece of link mesh fabric, an annulus provided with a plurality of circumferential receptacles for holding staples, a shuttle in said annulus, a tool mounted on said shuttle for forming staples in said receptacles, a link forming tool, an ejector mounted on said shuttle for discharging staples from said receptacles and cooperating with the link forming tool to form links intermeshing with the fabric, means for reciprocating said shuttle, and devices for actuating said annulus and for shifting the fabric step by step to align each staple with the link forming tool and to present different portions of the fabric to the tool to receive links.

In testimony whereof I affix my signature.

ALPHONSO COMSTOCK PRATT.
